CLAIM

The ornamental appearance of a shouldered round nose bullet, as shown and described.

DESCRIPTION

FIG. 1 is a perspective view of a bullet in accordance with the design;

FIG. 2 is a side elevation view thereof, the bullet being rotationally symmetric about its longitudinal axis; and,

FIG. 3 is a top plan view thereof the rear end of the bullet does not form a part of my design.

The rear elevation view is not shown and does not form a part of the claimed design.
